STRAND TWISTING APPARATUS

Tillman T. Bunch, near Ashland, Baltimore County, Md., assignor to Western Electric Company, Incorporated, New York, N.Y., a corporation of New York

Application July 22, 1955, Serial No. 523,911

10 Claims. (Cl. 57—58.52)

This invention relates to strand twisting apparatus and more particularly to apparatus for twisting a plurality of strands together into a single compact cable.

In the use of conventional strand twisting apparatus, in which a pair of spaced flyers are rotated at opposite ends of a reel-supporting cradle from which strands are withdrawn and twisted into a cable, considerable difficulty has arisen previous due to the tension necessary to restrict the ballooning of a normally unsupported length of the cable passing between sheaves on the outer ends of the rotating flyer arms to within workable limits. Due to centrifugal forces, this ballooning of the cable increases as the rotational speeds of the flyer arms are increased and, accordingly, imposes serious limitations upon the operating speeds of conventional strand twisting apparatus because of the danger of breakage or fouling of the cable.

The problem becomes more acute when such strand twisting apparatus is designed to accommodate strand supply reels of relatively large dimensions to obtain longer continuous production runs. To allow the loading and unloading of such large strand supply reels, the design of conventional stranding apparatus necessitates relatively long spans which the cable must traverse, thereby aggravating the problem of restricting the ballooning at high speed operation.

In conventional bow type stranders, tube type stranders or variants of these types, rotating cable supporting means incur the same detrimental centrifugal loading that the cable experiences and must rely either on loaded beam structures or on catenary type tension members to support the centrifugal loading. It is recognized generally that these structures develop inherently much greater stresses under centrifugal loading than are developed in hoop-like structures.

It is an object of this invention to provide new and improved strand twisting apparatus.

It is another object of this invention to provide new and improved apparatus for twisting a plurality of strands together into a single compact cable.

Apparatus embodying certain features of this invention may include a strand supply, means for withdrawing a strand from the strand supply, rotatable means for carrying a loop of the strand rotatably about the strand supply as the strand is withdrawn therefrom, and a rotatable hoop mounted concentrically with respect to the rotational axis of the rotatable means for engaging the strand loop and restraining the ballooning thereof.

In a specific embodiment of this invention, a plurality of spaced, circular hoops are positioned between the rotating flyer arms of a conventional strand twisting apparatus. The internal diameters of the hoops are such that they tend to restrain the ballooning of the length of the cable passing between guide sheaves on the extremities of the rotating flyer arms. The hoops are supported concentrically with respect to the common rotational axis of the rotating flyer arms and are driven in synchronism

2

with the flyer arms so that there is substantially no relative rotational movement between the hoops and the advancing cable at the points of contact therebetween. The hoops function to restrain the ballooning of the cable between the flyer arms and reduce the tensile stresses in the cables created by centrifugal forces.

A complete understanding of the invention may be had from the following detailed descriptions of apparatus forming specific embodiments thereof, when read in conjunction with the appended drawings, in which:

Fig. 1 is a side elevation of strand twisting apparatus embodying the invention;

Fig. 2 is an enlarged, side elevation of a flyer unit forming a part of the strand twisting apparatus illustrated in Fig. 1, with parts thereof broken away for clarity;

Fig. 3 is a vertical section taken along line 3—3 of Fig. 2;

Fig. 4 is a fragmentary, end elevation of a hoop forming a part of a modified embodiment of the invention, and

Fig. 5 is an enlarged vertical section taken along line 5—5 of Fig. 4.

Referring now to Fig. 1, there is shown strand twisting apparatus which includes a flyer unit, indicated generally at 10, and a takeup unit, indicated generally at 12. Both of these units are driven by a motor 14 through a conventional gear reducer 15 designed to rotate a drive shaft 16 journalled rotatably in antifriction bearings 17—17. The takeup unit 12 comprises a takeup capstan 20 and a takeup reel 21 which are connected to the driven shaft 16 through conventional transmission means (not shown) so that the takeup capstan and takeup reel are driven by the motor 14 at predetermined speeds and in timed relation with one another and the flyer unit 10.

Referring now to Fig. 2, the flyer unit 10 includes two flyer supporting studs, designated generally by the numerals 24 and 25 which are journalled rotatably in bearing blocks 27 and 28, respectively, mounted fixedly on spaced support columns 31 and 32, respectively. Both of the flyer supporting studs 24 and 25 are driven rotatably from the drive shaft 16 by means of conventional sprocket and chain transmissions, indicated generally at 34 and 35, respectively. The flyer supporting stud 24 is provided with an axially extending bore 37 which communicates with a radially extending slot 38 formed therein. A pair of freely rotatable guide pulleys 40—40 are positioned in the slot 38 on opposite sides of the longitudinal axis of the bore 37. The flyer supporting stud 24 has projecting, opposed, spaced flyer arms 42—42, and grooved guide sheaves 45 and 46 are journalled rotatably between the adjacent ends of the flyer arms.

The flyer supporting stud 25 is similar in construction to the flyer supporting stud 24 and is provided with a radially extending slot 48, in which is positioned a pair of freely rotatable guide pulleys 50—50. The guide pulleys 50—50 are positioned on opposite sides of the longitudinal axis of an axially extending bore 51 formed in the flyer supporting stud 25 in communication with the slot 48. The flyer supporting stud 25 is provided with projecting, opposed flyer arms 52—52 substantially identical in construction to the flyer arms 42—42 of the flyer supporting stud 24. Grooved guide sheaves 55 and 56 are journalled rotatably between the adjacent ends of the flyer arms 52—52.

The end of the flyer supporting stud 24, which extends toward the other flyer supporting stud 25 is provided with a projection 59 of a reduced diameter, through which the bore 37 extends completely. The projection 59 cooperates with a similarly configured projection 60 provided on the flyer supporting stud 25 to constitute trunnions for supporting a cradle, designated generally by

the numeral 65, in position between the flyer arms 42—42 and 52—52 where the cradle remains substantially stationary during rotation of the flyer arms with their respective flyer supporting studs 24 and 25 about the cradle.

The cradle 65 includes a rectangular framework made up of two longitudinally extending side members 69—69 which are secured to and spaced apart at their opposite ends by two crossmembers 70 and 71. The crossmembers 70 and 71 are provided with aligned apertures 74 and 75, respectively, which the trunnion projections 59 and 60 on the flyer supporting studs 24 and 25, respectively, are designed to enter to support the cradle. The apertures 74 and 75 are positioned so that the center of gravity of the cradle lies in a plane below the rotational axis of the flyer supporting studs.

In the cradle 65 there are positioned two strand supply reels 81 and 82 which are mounted rotatably on reel supporting centers 84—84 between the side members 69—69. Suitable braking devices (not shown) are provided for controlling the tension on strands 87 and 88 as they are withdrawn from the supply reels 81 and 82, respectively, during the operation of the strand twisting apparatus. The strand 88, which is withdrawn from the supply reel 82, passes between guide pulleys 89 and 90 mounted on the cradle 65, which guide the strand to a stranding die 92 positioned in the entrance end of the bore 37 formed in the projection 59. The strand 87, which is withdrawn from the supply reel 81, passes directly through the stranding die 92 wherein it is twisted with the strand 88 to form a cable, designated generally by the numeral 93.

The cable 93 is advanced through the bore 37 and into the slot 38 wherein it passes in a clockwise direction, as viewed in Fig. 2, partly about the guide pulley 40, which directs the cable to the guide sheave 45 on the flyer arms 42—42. The cable 93 is advanced from the guide sheave 45 in a direction opposite to the direction in which it advanced through the bore 37 and is directed to the guide sheave 55 on the flyer arms 52—52 from whence it advances partly around the guide pulley 50 and emerges from the flyer unit 10 through the bore 51 in the flyer supporting stud 25. After leaving the flyer unit 10, the cable 93 passes completely around the takeup capstan 20 and is finally wound up on the takeup reel 21.

Encircling the cradle 65 between the flyer arms 42—42 and 52—52 are three equally spaced hoops 95—95 formed from tubular metal stock, such as aluminum tubing or the like. Each of the hoops 95—95 is supported for rotation concentrically with respect to the rotational axis of the flyer supporting studs 24 and 25 by an associated equilaterally spaced arrangement of three grooved rollers 96, 97 and 98 (Fig. 3) which are positioned 120° apart in a common plane perpendicular to the rotational axis. The rollers 96—96, 97—97 and 98—98 are keyed upon horizontally extending shafts 101, 102 and 103, respectively, which are spaced equidistantly around the flyer unit 10.

The shaft 101 is supported freely rotatably at opposite ends thereof by a pair of spaced, projecting bracket arms 107—107. The bracket arms 107—107 are connected pivotally to spaced, vertical columns 108—108, respectively, on stub shafts 109—109. Each of the bracket arms 107—107 is provided with a suitable counterweight 110, which is designed to maintain the bracket arms in a raised position, as indicated by phantom lines in Fig. 3, whenever the center of gravity of the counterweights is positioned to the left of the stub shafts 109—109. Normally, the bracket arms 107—107 are in an operative position, as indicated in Fig. 3 by solid lines, in which position the rollers 96—96 on the shaft 101 engage the hoops 95—95.

The shafts 102 and 103 are journalled rotatably on spaced vertical support columns 112—112. The shaft

102 is freely rotatable, whereas the shaft 103 is driven positively by means of a sprocket and chain transmission, designated generally by the numeral 114 from a shaft 115. The shaft 115 is driven, in turn, from the drive shaft 16 by means of intermeshing gears 116 and 117. Each of the hoops 95—95 is driven rotatably by virtue of the frictional engagement with its corresponding, positively driven roller 98.

As shown in Fig. 2, the inner diameter of each of the hoops 95—95 is substantially equal to the diameters of the circular paths of travel of the support points at which the cable 93 leaves and enters the guide sheaves 45 and 55, respectively. Thus the hoops 95—95 function to restrain the ballooning of the otherwise unsupported length of cable 93 between the guide sheaves 45 and 55. By virtue of the intermeshing gears 116 and 117 the shaft 103 is driven in a direction and at a speed such that the hoops 95—95 rotate in the same direction as the rotating flyer arms 42—42 and 52—52 and the peripheral speeds of the hoops and the cable 93 at the points of contact therebetween are substantially equal.

Operation

25 It will be assumed, for the purpose of the following description, that the motor 14 has been energized to drive the flyer unit 10, and the takeup unit 12. Throughout the operation the takeup capstan 20 advances the cable 93, which is formed in the flyer unit 10, continuously to the takeup reel 21 upon which the finished cable is wound for storage. As the takeup capstan 20 advances the cable 93 longitudinally, the strands 87 and 88 are withdrawn from their respective strand supply reels 81 and 82 and enter the stranding die 92 wherein they are twisted together to form the cable.

30 Upon emerging from the stranding die 92, the cable 93 advances partly around the guide pulley 40 and is directed to the guide sheave 45 on the outer end of the flyer arms 42—42. From the guide sheave 45 the cable 93 advances to the guide sheave 55 on the outer end of the flyer arms 52—52 and thence to the guide sheave 50 which directs it through the bore 51 toward the takeup capstan 20. For each revolution of the flyer arms 42—42 and 52—52 two twists are imparted to the strands 87 and 88. Assuming a given rotational speed of the takeup capstan 20, the speed of rotation of the flyer arms 42—42 and 52—52 determines the number of twists of the strands 87 and 88 per unit length of the cable 93, that is, the greater the speed of rotation of the flyer arms the greater the number of twists per unit length of the cable.

35 As the flyer arms 42—42 and 52—52 are rotated, the length of cable advancing continuously between the guide sheaves 45 and 55 tends to balloon and, if it were not for the hoops 95—95, it would assume a single catenary configuration. The ballooning effect increases with increases in the rotational speed of flyer arms 42—42 and 52—52, due to the increasing centrifugal forces. Accordingly, the tensile stresses in the cable 93 increase with the increased centrifugal forces.

40 Since the hoops 95—95 have an internal diameter substantially equal to the diameters of the circular path of travel of the support points at which the cable 93 leaves and enters the guide sheaves 45 and 55, respectively, the ballooning of the length of cable 93 crossing the span between these guide sheaves is restrained and the hoops serve to support the cable at three equally spaced points therebetween. The effect is to break the usual single catenary into four smaller catenaries, whereby tensile stresses in the cable 93 along the length thereof between the guide sheaves 45 and 55 are greatly reduced. This permits the flyer unit 10 to be operated at relatively higher operating speeds without danger of breakage in the cable 93. It may be seen that any desired number of hoops 95—95 may be employed to break the usual

single catenary into smaller catenaries, and the tensional stresses in the cable 93 will be reduced accordingly.

An important feature of this invention is that the loading and unloading of strand supply reels 81 and 82 is made possible by making the rollers 96-96 movable manually out of engagement with the hoops 95-95, as shown in phantom lines in Fig. 3. The hoops 95-95 may then be lifted from the rollers 97-97 and 98-98 and shifted longitudinally to permit the strand supply reels 81 and 82 to pass therebetween. Thus the spacing between the hoops 95-95 is not dictated by the size of the strand supply reels employed.

Modified embodiment

Referring now to Fig. 4, there is shown a hoop 295 forming a part of a modified embodiment of the invention. The hoop 295 differs in construction from the hoops 95-95 primarily in that the hoop 295 has been provided with an antifriction sheave 298. The sheave 298 (Figs. 4 and 5) is rotatable freely about a pin 299 supported at opposite ends thereof between the sides of a U-shaped, combination support and guard, designated generally by the numeral 300, which is attached fixedly to the hoop 295. The sheave 298 is designed so that its weight is a minimum and the weight distribution of the hoop 295 is balanced preferably by internally disposed weights (not shown) positioned suitably therewithin.

Operation of the modified embodiment

In strand twisting operations involving strands having outer surfaces which possess relatively high coefficients of friction, it is desirable to utilize a hoop like the hoop 295 in place of each of the hoops 95-95. Assuming that three hoops like the hoop 295 have been substituted for the three hoops 95-95 of the apparatus described in the first embodiment of the invention, the cable 93 will advance longitudinally on the sheave 298 secured to each hoop during the twisting operation, whereby the friction is substantially reduced at the points at which the hoops support the cable. Since the sheave 298 on each hoop 295 must be aligned precisely at all times during the operation with the sheave on every other hoop, it is important that the hoops be rotated in synchronism by suitable means.

Manifestly, the embodiments of the invention hereinabove described are illustrative only and may be modified and departed from in various ways without departing from the spirit and scope of the invention.

It will be understood that although the above-described embodiments of the invention include three hoops, the invention is not limited to any specific number of hoops. For example, in some applications it may be expedient to use only one or two hoops, whereas in other applications it may be expedient to use four or more hoops.

In the above-described embodiments, the hoops have been described as having been constructed from tubular stock to reduce the weight thereof so that they may be supported and handled more readily. However, it will be understood that the hoops may be constructed from solid or tubular stock, as desired.

The term "twisting" as employed in the specification and claims is meant to include twisting, stranding and similar types of operations.

What is claimed is:

1. Strand twisting apparatus, which comprises a strand supply, means for withdrawing a strand from the strand supply, rotatable flyer means for carrying a loop of the strand rotatably about the strand supply as the strand is withdrawn therefrom, a hoop mounted concentrically with respect to the rotational axis of the flyer means, means for rotating the hoop in synchronism with the rotational flyer means, and antifriction means mounted on the hoop engaging the strand loop and restraining the ballooning thereof.

2. Strand twisting apparatus, which comprises a pair

of spaced flyer members rotatable about a common rotational axis, means for advancing a group of strands from the periphery of one flyer member to the periphery of the other, means for rotating the flyer members in synchronism, a hoop positioned intermediate of the flyer members and encircling the span of grouped strands advancing between the flyer members so as to restrain the ballooning of the strands as the flyer members are rotated, and means for detachably supporting the hoop for rotation concentrically about the rotational axis of the flyer members.

3. Strand twisting apparatus, which comprises a pair of spaced flyer members rotatable about a common rotational axis, means for advancing a group of strands from the periphery of one flyer member to the periphery of the other, means for rotating the flyer members in synchronism, a hoop positioned detachably intermediate of the flyer members and encircling the span of grouped strands advancing between the flyer members for restraining the ballooning of the strands as the flyer members are rotated, and means for rotating the hoop concentrically about the rotational axis of the flyer members at a rotational speed substantially equal to and in the same direction as the flyer members.

4. Strand twisting apparatus, which comprises a pair of spaced flyer members rotatable about a common rotational axis, means for advancing a group of strands from the periphery of one flyer member to the periphery of the other, means for rotating the flyer members in synchronism, a plurality of spaced rotatable hoops positioned intermediate of the flyer members and encircling the span of grouped strands advancing between the flyer members for restraining the ballooning of the strands as the flyer members are rotated, and means for supporting the hoops for rotation concentrically about the rotational axis of the flyer members.

5. Strand twisting apparatus, which comprises a pair of spaced flyer members rotatable about a common rotational axis, means for advancing a group of strands from the periphery of one flyer member to the periphery of the other, means for rotating the flyer members in synchronism, a plurality of spaced rotatable hoops positioned detachably intermediate of the flyer members and encircling the span of grouped strands advancing between the flyer members for restraining the ballooning of the strands as the flyer members are rotated, and means for supporting the hoops for rotation concentrically about the rotational axis of the flyer members.

6. Strand twisting apparatus, which comprises a pair of spaced flyer members rotatable about a common rotational axis, means for advancing a group of strands from the periphery of one flyer member to the periphery of the other, means for rotating the flyer members in synchronism, a plurality of spaced hoops positioned intermediate of the flyer members and encircling the span of grouped strands advancing between the flyer members for restraining the ballooning of the strands as the flyer members are rotated, and means for rotating the hoops concentrically about the rotational axis of the flyer members at rotational speeds substantially equal to and in the same direction as the flyer members.

7. Strand twisting apparatus, which comprises a pair of spaced flyer members rotatable about a common rotational axis, means for advancing a group of strands from the periphery of one flyer member to the periphery of the other, means for rotating the flyer members in synchronism, a plurality of spaced hoops positioned detachably intermediate of the flyer members and encircling the span of grouped strands advancing between the flyer members for restraining the ballooning of the strands as the flyer members are rotated, and means for rotating the hoops concentrically about the rotational axis of the flyer members at rotational speeds substantially equal to and in the same direction as the flyer members.

8. Strand twisting apparatus, which comprises a pair of spaced flyer members rotatable about a common rotational axis, means for advancing a group of strands from the periphery of one flyer member to the periphery of the other, means for rotating the flyer members in synchronism, a plurality of hoops positioned intermediate of the flyer members and encircling the length of grouped strands passing between the flyer members so as to restrain the ballooning of said strands when the flyer members are rotating, a plurality of rollers 10 spaced around the hoops in peripheral rolling engagement therewith and designed to rotatably support the hoops concentrically with respect to the rotational axis of the flyer members and in spaced relation to one another, and means for rotatably driving at least one 15 roller in contact with each of the hoops to rotate the hoops simultaneously at rotational speeds substantially equal to and in the same direction as the flyer members.

9. Strand twisting apparatus, which comprises a pair of spaced flyer members rotatable about a common rotational axis, a cradle positioned floatingly between the flyer members, a plurality of strand supply reels mounted on the cradle, means for withdrawing the strands simultaneously as a group from their supply reels, guide means for directing the grouped strands from the periphery of one flyer member to the periphery of the other, means for rotating the flyer members in synchronism whereby the grouped strands are twisted together by being carried bodily around the cradle, a plurality of hoops positioned intermediate of the flyer members and encircling the length of grouped strands passing between the flyer members for restraining the ballooning of said strands when the flyer members are rotating, a plurality of rollers 35 spaced around the hoops in peripheral rolling engagement therewith and designed to rotatably support the hoops concentrically with respect to the rotational axis of the flyer members and in spaced relation to one another, means for rotatably driving at least one roller in contact with each of the hoops to rotate the hoops simultaneously 40 at rotational speeds substantially equal to and in the same direction as the flyer members, and means for disengaging the hoops from their respective supporting

rollers so that the individual hoops may be shifted axially to allow the strand supply reels to be loaded and unloaded on the cradle.

10. Strand twisting apparatus, which comprises a pair of spaced flyer members rotatable about a common rotational axis, a cradle positioned floatingly between the flyer members, a plurality of strand supply reels mounted on the cradle, means for withdrawing the strands simultaneously as a group from their supply reels, guide means for directing the group strands from the periphery of one flyer member to the periphery of the other, means for rotating the flyer members in synchronism whereby the grouped strands are twisted together by being carried bodily around the cradle, a plurality of tubular hoops positioned intermediate of the flyer members and encircling the length of grouped strands passing between the flyer members, antifriction sheaves mounted on the hoops for rotation therewith and designed to rollingly engage the strands and restrain the ballooning of staid strands when the flyer members are rotating, a plurality of rollers spaced around the hoops in peripheral rolling engagement therewith and designed to rotatably support the hoops concentrically with respect to the rotational axis of the flyer members and in spaced relation to one another, means for rotatably driving at least one roller in contact with each of the hoops to rotate the hoops in synchronism at rotational speeds equal to and in the same direction as the flyer members, and means for disengaging the hoops from their respective supporting rollers so that the individual hoops may be shifted axially to allow strand supply reels to be loaded and unloaded on the cradle.
